UNITED STATES PATENT OFFICE.

HARTLEY ELLIS, OF CLEVELAND, OHIO.

METAL BARREL OR RECEPTACLE.

1,341,304.

Specification of Letters Patent. Patented May 25, 1920.

Application filed April 26, 1917. Serial No. 164,620.

To all whom it may concern:

Be it known that I, HARTLEY ELLIS, a citizen of the United States of America, residing at Cleveland, in the county of Cuyahoga and State of Ohio, have invented certain new and useful Improvements in Metal Barrels or Receptacles; and I hereby declare the following to be a full, clear, and exact description of the invention, such as will enable others skilled in the art to which it pertains to make and use the same.

This invention relates to improvements in metal barrels or receptacles, and pertains more especially to a metal receptacle having its body comprising a vertically arranged or upright tubular metal shell which is circular in plan and has its upper end-portion contoured as required to receive a head or closure for the receptacle.

20 The primary object of this invention is to produce a metal receptacle of the character indicated which is strong and durable and light in weight and can be cleaned internally and manufactured with facility.

25 With this object in view, and to the end of attaining any other object hereinafter appearing, this invention consists in certain features of construction and combinations and relative arrangement of parts, herein-30 after described in this specification, pointed out in the claim, and illustrated in the accompanying drawings.

In said drawings, Figure 1 is a side elevation of the upper end-portion of a metal barrel or receptacle embodying my invention, and portions are broken away in this figure to more clearly show the construction. Fig. 2 is a top plan relative to Fig. 1. Fig. 3 is a central vertical section taken along the 40 line 3-3, Fig. 1. Fig. 4 is an enlarged view of a portion of Fig. 3.

The body of my improved metal barrel or receptacle comprises a vertically arranged or upright metal shell A of which only the 45 upper end-portion is illustrated in said drawings. Said shell is preferably circular in plan. The upper end-portion of said shell is shown provided externally with a laterally and outwardly projecting annular rib 50 a spaced from but arranged in suitable proximity to the upper extremity and extending circumferentially of said shell.

Said end-portion of said shell has two circumferentially extending vertically spaced 55 annular laterally and inwardly offset portions 6 and 7 which are integral with the

body A and arranged between the rib a and the upper extremity of said shell, and each of said offset portions forms an annular recess 10 arranged at the exterior and extending circumferentially of said shell. It will be observed therefore that the offset portions 6 and 7 not only form two vertically spaced recesses 10 externally of the shell A but also form an annular recess 11 between 65 said offset portions internally of said shell, and that all of said recesses are arranged concentrically.

The bottom of the upper offset portion 6 of the shell A forms a downwardly facing 70 substantially horizontally arranged annular shoulder 12 internally of said shell, and said upper offset portion flares toward its upper end.

The top of the lower offset portion 7 of 75 the shell A forms an upwardly facing substantially horizontally arranged annular shoulder 13 internally of said shell, and said lower offset portion flares toward its lower end to facilitate internal cleaning of the receptacle below the recess 11 formed, as already hereinbefore indicated, between the offset portions 6 and 7. The shoulder 13 formed by the top of the lower offset portion 7 of the shell A forms an annular seat 80 extending farther inwardly than the shoulder 12 formed at the bottom of the upper offset portion 6 of said shell and consequently extends farther inwardly than said upper offset portion. The seat 13 is arranged to support a head (not shown) to be employed as a closure for the receptacle, and the recess 11 between the offset portions 6 and 7 of the shell A is large enough vertically to receive said head and means (not 90 shown) employed in locking or holding said head tightly against said seat.

I would here remark that the offset portions 6 and 7 of the shell A materially reinforce the upper end-portion of said shell, 100 but to still further strengthen said end-portion of said shell an annular reinforcing metal band B, preferably of steel, is provided which band surrounds said shell and is arranged next above the rib a and extends upwardly from said rib across the recesses 10 and therefore forms a closure for said recesses. Said band preferably snugly embraces and extends circumferentially of the shell A between the recesses 10, and consequently between the offset portions 6 and 7 110 of said shell and above the upper offset por-

tion 6 and below the lower offset portion 7, and therefore materially reinforces said shell between and above and below said offset portions.

- 5 The band B is provided at its upper end with a laterally and outwardly projecting rounded annular flange b extending circumferentially of the band, and the shell A is provided at its upper end with a laterally 10 and outwardly projecting annular member 14 extending over and thence downwardly across the outer circumferential edge of and under said flange and into an annular recess 15 formed, preferably next below said flange, in the outer side of and extending circumferentially of said band. The member 14 of the shell A preferably snugly embraces the flange b as shown, and is instrumental in preventing displacement of the band B end- 20 wise of said shell in either direction. It will be observed therefore that the annular member 14 has its portion which extends under the flange b serving as a support for the band B, and, of course, the rib a, being ar- 25 ranged next below said band, as shown, positively prevents descent of the said band.

I would here remark that the shell A is preferably formed of a single steel plate or sheet rolled or otherwise operated on to 30 form the offset portions 6 and 7 and the rib a and bent to form said shell, that the laterally and outwardly projecting member 14 of said shell is not formed until after the application, to said shell, of the reinforcing band B, and that said member 14 is formed 35

by spinning or otherwise operating on the upper end of the section forming said shell upon the application of said band.

What I claim is:—

In a receptacle, the combination, with a 40 body comprising an upright metal shell which is circular in plan and has its upper end portion provided externally with a rib spaced from the upper extremity and extending circumferentially of said shell, said 45 end portion of said shell being provided between its upper end and said rib with two circumferentially extending and vertically spaced laterally and inwardly offset annular portions, the bottom of the upper offset por- 50 tion forming a downwardly facing annular shoulder internally of said shell, the top of the lower offset portion forming an upwardly facing annular seat-forming shoulder internally of said shell, and said offset 55 portions forming vertically spaced annular recesses arranged at the exterior and circumferentially of said shell, of a reinforcing band embracing the aforesaid end portion of said shell and forming a closure for said 60 recesses, said band being supported at its upper end portion from said shell and being arranged next above the aforesaid rib.

In testimony whereof, I sign the foregoing specification, in the presence of two 65 witnesses.

HARTLEY ELLIS.
